[57] CLAIM

The ornamental design for a figurine of a doberman pinscher, substantially as shown and described.

DESCRIPTION

FIG. 1 is a front end perspective view of the figurine of a doberman pinscher showing our new design;
FIG. 2 is a side elevational view of FIG. 1;
FIG. 3 is an opposite side perspective view showing the side opposite that shown in FIG. 2; and
FIG. 4 is a rear end perspective view of FIG. 1.
